AUTOMOBILE WHEEL

Kenneth S. Goodwin, Torrance, Calif., assignor to Rebel Wheel Co. Inc., San Pedro, Calif., a corporation of California

Filed Apr. 9, 1965, Ser. No. 84,693

Term of patent 14 years

(Cl. D14—30)

FIG. 1 is a perspective view of an automobile wheel, showing my new design;

FIG. 2 is a front elevational view thereof;

FIGS. 3 and 4 are sectional views thereof taken respectively along lines 3—3 and 4—4 of FIG. 2; and

FIG. 5 is a rear elevational view thereof.

I claim:

The ornamental design for an automobile wheel, substantially as shown.
